FLUID CONTAINER

Leo Simon Breitmann, Paris, France, assignor to
 Pyrene Manufacturing Company, Newark, N. J.,
 a corporation of Delaware

Application March 17, 1936, Serial No. 69,250
 In Germany March 25, 1935

1 Claim. (Cl. 169—11)

This invention relates to fluid containers which are adapted to retain therein carbonic acid in two phases, namely, gas and liquid, to be released under pressure for use in the production of so-called carbonic acid snow.

Heretofore containers of the above type have been equipped in some instances with pick-up tubes, and in other instances such tubes have been omitted.

10 It is obvious that if the former type of container, namely one equipped with a pick-up tube according to prior practice, is held in a vertical position with its exit end uppermost, the liquid content will be expelled prior to and under the action of the gaseous content, whereas if such tube is inverted the entire content will be expelled as a gas. It is also obvious that if the latter type of container is held in a vertical position with its exit end uppermost its entire content will be released as a gas, whereas if such type is inverted its liquid content will be expelled prior to and under the action of its gaseous content.

From the foregoing, it will become apparent that neither of the above-described containers (in each of the positions mentioned) will insure discharge of its liquid content in liquid phase.

An important object of the present invention is to provide a container which is adapted to retain therein carbonic acid in two phases, namely, gas and liquid, and which is structurally such as to insure discharge of the liquid content in liquid phase regardless of the position in which the container is held.

To the above and other ends the invention contemplates a container having an outlet passage communicating with a pick-up tube, the container being provided at its exit end with a plurality of ducts which convergently lead from the container toward the exit end thereof and by which communication is maintained between the pick-up tube and the container in the vicinity of its exit end, the combined cross-sectional areas of such ducts being equal to the cross-sectional area of the pick-up tube passage in order to effect an equalization, with regard to rates of discharge, as between the gas and the liquid contents of the container.

Although the invention may be utilized in connection with carbonic acid containers generally, it is herein illustrated as embodied in and forming a part of a container unit, equipped with a funnel-like nozzle or directing element which renders the unit admirably adapted for use as a fire extinguisher.

In the drawing—

Fig. 1 is a view partly in section and partly in elevation of one form of the invention; Fig. 2 is an enlarged fragmental view partly in section and partly in elevation of another form of the invention, and Fig. 3 is a transverse sectional view taken on line 3—3 of Fig. 2.

Referring particularly to Fig. 1 of the drawing, the numeral 5 indicates a container, of the so-called cartridge type, adapted to retain therein carbonic acid in two phases, namely, gas and liquid, to be released under pressure and to be used in the production of so-called carbonic acid snow. It will be observed that above the level of the liquid content 6, there is afforded a substantial space which is adapted to accommodate the gas content of the container. It will be understood, of course, that when the container is inverted the gas-accommodating space will then be afforded, above the liquid level indicated by dot and dash lines, at the opposite end of the cartridge.

The exit end of the cartridge is provided with a control valve 7, comprising a housing 8 which includes a pair of screw threaded coupling elements 10 and 11, the former of which is adapted for screw threaded connection with the neck of the container and the latter of which is adapted to receive a directing element, herein shown as a funnel-like nozzle 12 which renders the unit admirably adapted for use as a fire extinguisher.

Disposed within and secured to the coupling element 10, is a pick-up tube 14 which is substantially coextensive with the container 5, so that its inlet end is disposed relatively near the inner wall of the cartridge at the closed end thereof. This pick-up tube is adapted to communicate with the nozzle 12 by way of a series of ducts 15, 16, 17, and 18, constituting an outlet passage, which may be opened or closed at will by a valve 20, equipped with a manually operable hand wheel 21 to facilitate movement of the valve in one direction or the other as occasion may require.

In order that direct communication may be afforded between the container 5 and the pick-up tube 14 at or in the vicinity of its exit end, the coupling element 10 is provided with a plurality of ducts 22, which converge toward the axis of the pick-up tube and register with a corresponding number of port-like apertures 24 formed in that portion of the pickup tube which is secured within the coupling element. As to the ducts 22 and apertures 24, it may be well to here emphasize the fact that the total effective area of the several paths of communication which are

afforded by such ducts and apertures is equal to the cross-sectional area of the passage afforded through the pick-up tube 14.

The operation of the apparatus above described is such that, when the valve 20 is opened (assuming the container 5 to be positioned with its exit end uppermost), liquid 6 will be forced, under the action of gas pressure above the level thereof, upwardly through the pick-up tube 14, and gas 10 will pass from the space afforded above the liquid level into the exit end of the pick-up tube, by way of the ducts 22 and the apertures 24, and will there commingle with the liquid to effect a discharge-stream composed of both liquid and gas. 15 If, however, the cartridge is held, during the discharge period, with its exit end lowermost, liquid will be discharged, under the action of gas pressure above the same, by way of the ducts 22 and the apertures 24, and gas will enter the pick-up 20 tube, by way of its then uppermost end, and will be delivered to and commingled with the liquid as it enters that tube by way of said ports and said apertures.

Inasmuch as the effective passage area of the 25 pick-up tube 14 is equal to the combined effective area of the ducts 22 and inasmuch as these ducts convergingly lead from the container toward the exit end thereof and maintain communication between the container and the pick-up tube, there 30 will be effected an equilibrium with regard to rates of discharge as between the gas and the liquid contents of the container, regardless of whether the container is operated in an upright or in an inverted position. For example, if the 35 gas pressure is such that it tends to escape at too rapid a rate with respect to the rate of discharge of the liquid, its escape is impeded by reason of the fact that it exerts an ejector action on the liquid thus increasing the rate of discharge 40 of the liquid incident to a decrease in the rate of discharge of the gas; whereas, if the liquid should tend to escape at too rapid a rate with respect to the gas (as might possibly happen when the container unit is inverted due to the head of liquid) its escape is impeded by reason of the fact 45 that it exerts an ejector action on the gas which

is then adapted to enter the pick-up tube at the inlet end thereof, thus increasing the rate of discharge of the gas incident to a decrease in the rate of discharge of the liquid.

Referring to Figs. 2 and 3, wherein primed reference characters are employed to indicate parts which are similar to those already described in connection with Fig. 1, it will be observed that the hand wheel 21', which is adapted to move the valve (not shown but corresponding of course to the valve 20) to opened and closed positions, is arranged at the end of the valve housing rather than at the side thereof, and that the funnel-like nozzle 12' is attached to the valve housing at the side thereof rather than at the end thereof. 15

In view of the fact that the changes which are peculiar to the form of apparatus shown in Figs. 2 and 3 may be adapted without in any way modifying the operation of the invention as already described, it is believed that any detailed description of the operation of the modified structure is here unnecessary.

Aside from the modifications above described, it will be understood that various other changes may be made without departing from the spirit 25 of the invention or the scope of the following claim.

What is claimed is:

A fluid container unit comprising a container adapted for the retention of a compressible fluid 30 in two phases, namely, gas and liquid, to be released; a coupling element carried at one end of said container and having an outlet passage and provided with a plurality of ducts grouped about said passage and convergingly leading from the 35 interior of said container toward the axis of said passage; and a pick-up tube disposed within and extending longitudinally of said container, said pick-up tube being in communication at its inlet end with said container at a point longitudinally 40 remote from said coupling element and also communicating with said container by way of said ducts, the effective passage-area of said pick-up tube being equal to the combined effective area of said ducts.
